John Dutton's Design for an Ornamental Fountain

John Dutton,

Delaware County Penn²Cotter's patent (Design No 90.) dated 3rd October 1846

The schedule referred to in these Cotter's Patent and accompanying part of the same.

Be it known that I, John Dutton of Aston Township, Delaware County, State of Pennsylvania, have invented a new design for a fountain, which is described as follows reference being had to the annexed drawings of the same making part of this specification.

Figure 1 is a perspective view of the fountain.

The nature of this design for an ornamental fountain consists in combining with a hollow stationary column, (into which the water flows from a reservoir placed at a higher level) a revolving head and circular plate - a number of ^{hollow} radial arms, made to curve or twist upward and connect with a number of small hollow revolving heads by suitable couplings - from which heads, radiate smaller hollow arms curved at their outer extremities & from which heads there also rise spiral or serpentine tubes each being perforated over its surface with very small perfora-

tions in a continuous spiral line from the bottom to the top for the escape of the water in small jets sufficient to form a beautiful spray, the radial tubes being also perforated where they are curved— the perforations in said tubes being so made that the water shall escape in a direction contrary to that in which the arms turn. The jets of water and spray are reflected by prisms of glass placed on top of the central revolving spherical head & appended to the edge of the horizontal circular plate attached to and turning with the head.

A is the hollow column. B is the base of the column. C is the revolving hollow head, D is the circular plate attached to the plate and turning with it. E is the coupling of the head. F are the large hollow radial arms with curved ends. — G are small revolving heads coupled to the radial arms by the Coupling H. — I are small ^{hollow} radial arms inserted into the small heads and curved at their outer ends. — K are the serpentine tubes which rise upward from the tops of the small revolving heads. The apertures in the radial arms & tubes are made in the convex portions of their curved ends and nearly horizontal, or inclining slightly upward and the apertures in the spiral tubes incline upward at an angle of about 45 degrees with a horizontal plane.

When the water is let on to the fountain it instantly fills the hollow column—the revolving heads— arms and curved and spiral tubes and issues through the small perforations in jets proportionate to the sizes of the perforations— causing the arms to turn in the direction of the arrows A. 2. and the water to escape in the direction of the arrows A. 3. The water will issue from the spiral tubes in the direction of the spiral lines of perforations and form a beautiful serpentine spray which will be reflected by the glass prisms in many figures and colors; and at the end of each spiral tube there will be a vertical jet— which will also be reflected by the glass prisms; which jet will issue in the direction of the arrow A. 3. The water will issue from the curved arms I. in the direction of the arrow A. 4. causing them to turn in the direction of the arrows A. 5. —

What I claim as my invention and wish to secure by Letters

3

Ref. 90

Patent is the design, here represented in the annexed drawings, of an ornamental fountain, whether it be made of iron, brass, wood, composition, glass or other materials.
